UNITED STATES PATENT OFFICE

HAROLD S. BLACK, OF EAST ORANGE, NEW JERSEY, ASSIGNOR TO WESTERN ELECTRIC COMPANY, INCORPORATED, OF NEW YORK, N. Y., A CORPORATION OF NEW YORK

PHANTOM CARRIER CIRCUIT

Application filed May 11, 1928. Serial No. 276,895.

This invention relates to wave transmission, and especially to phantoming multiplex systems, as for example carrier wave signaling systems.

Considering, for example, terminal apparatus for a pair of two-conductor lines each transmitting voice frequency waves and carrier waves, when it is desired to phantom the lines for either voice or carrier waves, 10 or both, for instance in the general manner disclosed in the patents to Affel 1,582,112 and 1,582,113 and O'Leary 1,582,073, all issued April 27, 1926, it is desirable to avoid deleterious effects in the phantom circuit 15 or circuits due to inclusion therein of side circuit filters used for frequency separation of the voice frequency waves and carrier frequency waves.

It is an object of the invention to avoid 20 such deleterious effects while economizing apparatus for effecting frequency separation of the different messages intended for the different signaling channels, respectively.

It is also an object to, at the same time, 25 economize with respect to the number of phantom coils required.

In one specific aspect the invention is a multiplex wave transmission system having side circuits with side circuit low frequency 30 grouping filters and side circuit high frequency grouping filters in the side circuits, and having a phantom circuit for low frequency waves, and/or a phantom circuit for high frequency waves derived from the side 35 circuits at such points thereof that waves pass through the low frequency phantom circuit without passing through the side circuit low frequency grouping filters and/or waves pass through the high frequency 40 phantom circuit without passing through the side circuit high frequency grouping filters. All of the filters mentioned may be of the usual construction, as may also any filters used in the phantom circuits to effect 45 frequency selection or separation of low frequency and/or high frequency waves intended for the low frequency and/or high frequency phantom circuits respectively. The use of side circuit filters and phantom circuit filters of usual construction tends to-

ward economy of filter apparatus, by facilitating an economical design of the individual filters.

The points in the side circuits at which the phantom circuits are derived may be at the junction of the transmission lines with the side circuit grouping filters. Thus, a given set of phantom coils may be employed for both phantom circuits, since the waves intended for the phantom circuits are derived from the side circuits before frequency separation of the low frequency waves and the high frequency waves intended for the phantom circuits.

Other objects and aspects of the invention 65 will be apparent from the following description and claims.

Fig. 1 is a diagram of a system embodying one form of the invention; and

Fig. 2 is a diagram of a system embodying another form of the invention.

Referring to Fig. 1, HFL and HFL' represent two telephone lines, each comprising a pair of conductors which may be phantomed in a well known manner so that each pair of conductors acting in parallel operates as one side of a phantom circuit. The phantom connections are established by means of transformers 10 and 10', from the middle points of whose windings taps 11 and 11' are led to form the phantom terminals of the system.

In order that the line HFL may be employed for carrier transmission, a branch CL_s is provided which leads to carrier equipment of any type well known in the art, and in this branch a high pass filter 12 is included. This high pass filter is of the broad band type which freely transmits a band of frequencies within certain limits, while sharply attenuating and suppressing the frequencies lying without the limits of the band. The filter is so designed as to pass the various carrier frequencies employed in the system together with their associated side bands, but it will not permit ordinary voice currents transmitted over the line HFL to pass into the circuit CL_s. The ordinary voice currents transmitted over the conductor HFL must be separated from the

carrier frequencies and transmitted through the transformer 10 to the voice side circuit channel VL_s . In order to accomplish this result, a low pass filter 13 is connected in the branch of the line circuit HFL leading to the voice side circuit VL_s . The filter 13 is of the broad band type and freely transmits all frequencies lying within the voice range while suppressing all frequencies above the voice range. The carrier frequencies are thereby prevented from entering the voice side circuit VL_s .

In a similar manner, the line HFL' is provided with two branches, one leading through the high pass filter 14 to the side carrier circuit CL' and the other leading through the low pass filter 15 to the voice side circuit VL' .

The arrangement so far described is that ordinarily employed for superposing a plurality of carrier channels on an ordinary voice channel. It is possible to phantom a pair of circuits of this type for ordinary voice transmission by means of the phantom coils 10 and 10' with their phantom conductors 11 and 11'. The voice currents transmitted over the phantom, in so far as any unbalance occurs between the two conductors of the side circuit, are prevented from entering the carrier circuit, such as the circuit CL_s , by the high pass filter. The effect upon the phantom of the filter LF_s in the two conductors of the side circuit in introducing impedance due to the series coils of the filter is objectionable, but this impedance is not intolerable at the ordinary voice frequencies. If, however, we attempt to transmit carrier frequencies over the phantom, the inductance of the series elements of the filter LF_s of LF'_s is relatively much greater, so that this problem must be overcome. The problem of selection between the carrier phantom and the voice phantom must also be overcome.

In accordance with the present invention it is proposed to provide a carrier phantom connection by introducing phantom coils, such as 20 and 20' between the lines HFL and HFL' and the high pass filters 12 and 14. Conductors 21 and 21' are led from the midpoints of the phantom coils, as indicated, to form the phantom carrier terminal CL_p , which leads to suitable carrier equipment. With this arrangement, the phantom carrier currents need not be transmitted through the impedance of any of the side circuit filters.

In order to provide the necessary frequency separation between the voice currents transmitted over the phantom and the carrier currents transmitted over the phantom, a low pass filter 16 is included in the voice phantom terminals VL_p and a high class filter 17 is included in the carrier phantom terminal CL_p . These filters are similar to

the high and low pass filter combinations already described and operate in the same manner. The necessity for these filters arises from the fact that the conductors of the voice phantom circuit are connected to the conductors of the carrier phantom circuit through the filters 13 and 15, so any dissymmetry in these filters cannot introduce phantom circuit impedance in the carrier phantom circuit.

The transformers 20 and 20' and transformer 22, enhance the balance of the telephone equipment when it is connected to a noisy or unbalanced line, and therefore serve to reduce noise caused, for example, by induction from power lines into lines HFL and HFL' or by "static" picked up in those lines.

Condensers 23 connected between the halves of the line windings of transformers 20, 20' and 22, facilitate transmission of ringing currents of, for example, 20 cycles or 133 cycles, from or to the lines HFL and HFL' .

Fig. 2 shows another form of the invention. Parts having the same reference characters in the two figures are identically alike in structure and function. The filters 12' to 15' of Fig. 2 are similar in structure and function to the filters 12 to 15 respectively, of Fig. 1, but may be of cheaper design, for reasons indicated hereinafter.

Thus, the system of Fig. 2 comprises the lines HFL and HFL' each transmitting voice and carrier frequencies, the side circuit low frequency grouping filters 13' and 15', the side circuit high frequency grouping filters 12' and 14', a phantom circuit VL_p for low frequency waves and a phantom circuit CL_p for carrier or high frequency waves. These phantom circuits are derived from the side circuits at the junctions of the transmission lines HFL and HFL' with the side circuit grouping filters, by employing phantom coils 30 and 30' for both phantom circuits. The low frequency waves and the carrier waves intended to be transmitted from the transmission lines HFL and HFL' to the phantom circuits VL_p and CL_p , are derived from the transmission lines before frequency separation of the low frequency waves and the carrier frequency waves; and these derived low frequency waves and carrier waves are separated by the filters 16 and 17.

Thus, the phantom circuits VL_p and CL_p , are derived from the side circuits at the line side of the side circuit grouping filters 12', 13', 14' and 15', so that the phantom circuits do not include side circuit grouping filters. Therefore, the deleterious effects which would result from inclusion of such filters are avoided.

The transformers 30 and 30', and transformer 33, reduce deleterious noise effects,

as noted of transformers 20, 20' and 23 in Fig. 1.

In Fig. 2, since the low frequency phantom path does not include the low pass filters of the side circuits, any dissymmetry in those filters cannot introduce impedance in the low frequency phantom circuit. Therefore, the filters 13' and 15' can be of cheaper design than the filters 13 and 15. Further, under conditions usual in practice, inclusion of low pass filters of side circuits in low frequency phantom paths introduces sufficient impedance to cause objectionable distortion or degradation of signal quality, and moreover, upset the impedance balance between the voice phantom circuit VL_p and its balancing network at the voice phantom circuit repeater hybrid coil or bridge transformer. (The repeater with the hybrid coil and the balancing network are not shown in the drawing, as it will be understood that it can be connected to the voice phantom circuit in the usual way).

In both figures of the drawing, all of the filters can be of the usual construction.

What is claimed is:

1. A multiplex wave transmission system comprising side circuits, side circuit low frequency grouping filters and side circuit high frequency grouping filters in the side circuits, and a phantom circuit derived from the side circuits at such points thereof with relation to said side circuit filters that waves transmitted over said side circuits pass through the phantom circuit without passing through either side circuit filter.
2. A multiplex wave transmission system comprising side circuits, side circuit low frequency grouping filters and side circuit high frequency grouping filters in said side circuits, a phantom circuit for low frequency waves, and a phantom circuit for high frequency waves, both derived from said side circuits at such points thereof with relation to said side circuit filters that waves intended for said phantom circuits leave the side circuits before frequency separation of the low frequency waves and the high frequency waves intended for the phantom circuits.
3. A multiplex wave transmission system comprising side circuits, side circuit low frequency grouping filters and side circuit high frequency grouping filters in the side circuits, and a phantom circuit derived from the side circuits at such points thereof with relation to said filters that the impedance of neither filter is included in the phantom circuit, each of said filters comprising series and shunt paths, and certain of said shunt paths consisting of a single reactance element.
4. A system comprising two side circuits and a phantom circuit derived therefrom, said side circuits including transmission lines and physical paths selective of waves of a

given frequency range, one of said paths having one end connected to one of said lines, and the other of said paths having one end connected to the other of said lines, said system also comprising, in addition to said side circuit selective paths, a physical path included in said phantom circuit and selective of waves of a frequency range substantially included in the first mentioned frequency range, said physical path being connected to said ends of said side circuit selective paths so that the latter paths are not included in said phantom circuit.

5. A system comprising two voice wave side circuits and a voice wave phantom circuit derived therefrom, said side circuits including voice wave transmission lines and voice wave physical paths selective of waves of given characteristics, one of said paths having one end connected to one of said lines, and the other of said paths having one end connected to the other of said lines, said system also comprising, in addition to said side circuit selective paths, a physical path for voice waves, included in said phantom circuit and selective of waves of given characteristics and connected to said ends of said side circuit selective paths, so that the latter paths are not included in said phantom circuit.

6. A system comprising two carrier wave side circuits and a carrier wave phantom circuit derived therefrom, said side circuits including carrier wave transmission lines and carrier wave physical paths selective of waves of given characteristics, one of said paths having one end connected to one of said lines, and the other of said paths having one end connected to the other of said lines, said system also comprising, in addition to said side circuit selective paths, a physical path for carrier waves, included in said phantom circuit and selective of waves of given characteristics and connected to said ends of said side circuit selective paths, so that the latter paths are not included in said phantom circuit.

7. A system comprising two signal transmission lines each adapted to transmit voice waves and carrier waves, a voice wave side circuit including one of said lines, a voice wave side circuit including the other of said lines, a voice wave phantom circuit derived from said lines, and a carrier wave phantom circuit derived from said lines, said voice wave side circuits including voice wave physical paths selective of waves of given characteristics, one of said voice wave paths having one end connected to one of said lines, and the other of said voice wave paths having one end connected to the other of said lines, said system also comprising, in addition to said side circuit voice wave selective paths, a physical path for voice waves, included in said voice wave phantom

- circuit and selective of waves of given characteristics and connected to said ends of said side circuit voice wave selective paths so that the latter paths are not included in said voice wave phantom circuit, said carrier wave side circuits including carrier wave physical paths selective of waves of given characteristics, one of said carrier wave paths having one end connected to one of said lines, and the other of said carrier wave paths having one end connected to the other of said lines, said system also comprising, in addition to said side circuit carrier wave selective paths, a physical path for carrier waves, included in said carrier wave phantom circuit and selective of waves of given characteristics and connected to said ends of said side circuit carrier wave selective paths, so that the latter paths are not included in said carrier wave phantom circuit.
8. The method which comprises transmitting different messages of different frequency ranges respectively over one path, transmitting different messages of different frequency ranges respectively over a second path, transmitting messages over said two paths in parallel, deriving from the two paths said messages transmitted over the two paths in parallel, to the exclusion of said other messages, and thereafter effecting frequency separation of said messages of different frequency ranges transmitted over the one path and frequency separation of said messages of different frequency ranges transmitted over the second path.
9. The method which comprises transmitting different messages of different frequency ranges respectively over one path, transmitting different messages of different frequency ranges respectively over a second path, transmitting different messages of different frequency ranges, respectively, over the two paths in parallel, deriving from the two paths said messages transmitted over the two paths in parallel, to the exclusion of said other messages, and thereafter effecting frequency separation of said messages of different frequency ranges transmitted over the two paths in parallel, frequency separation of said messages of different frequency ranges transmitted over the one path, and frequency separation of said messages of different frequency ranges transmitted over the second path.
- 55 In witness whereof, I hereunto subscribe my name this 10th day of May, 1928.

HAROLD S. BLACK.
